(57) **CLAIM**

The ornamental design for a modular tabletop section as shown and described.

DESCRIPTION

FIG. 1 is an isometric view of a modular tabletop section. FIG. 2 is a top plan view of the modular tabletop section of FIG. 1.

FIG. 3 is a bottom plan view of the modular tabletop section of FIG. 1.

FIG. 4 is a front elevation view of the modular tabletop section of FIG. 1.

FIG. 5 is a rear elevation view of the modular tabletop section of FIG. 1.

FIG. 6 is a left side elevation view of the modular tabletop section of FIG. 1.

FIG. 7 is a right side elevation view of the modular tabletop section of FIG. 1; and,

FIG. 8 is top plan view of the modular tabletop section of FIG. 1, shown in an environment of use.

Portions of FIGS. 1 through 8 are shown in evenly spaced broken lines illustrating portions of the article that form no part of the claimed design. The dash-dot-dot lines in FIG. 8 are directed to environment and form no part of the claimed design.
